UNITED STATES PATENT OFFICE

2,391,187

HYDRAULIC ARBOR PRESS

Herbert E. Page, Pasadena, Calif.

Application July 5, 1943, Serial No. 493,566

9 Claims. (Cl. 100—71)

This invention has to do with hydraulic presses, a more particular adaptation being as an arbor press.

One of the major features of my invention is its provision of novel means for obtaining quick contact of the ram with the work. This initial contact is accomplished either mechanically or hydraulically, by a simple, compact mechanism. After contact is made, my ram-actuating element is automatically converted from a quick contact establishing mechanism to a pressure multiplying mechanism which exerts the requisite pressure on the ram to accomplish its work.

Another feature of my invention resides in the provision of a single manually operated member for establishing quick contact of the ram with the work and for thereafter exerting the hydraulic working pressure, thus eliminating the multiplicity of controls usually necessary for the full operation of conventional arbor presses.

Another object of my invention is the provision of a safety clutch in combination with pressure release means to prevent injury which might result from return movement of the ram mechanism being transmitted to the manual control member, as well as to render it possible to disengage the operating means to maintain a fixed hydraulic pressure on the ram when desired.

An additional object of the invention is the elimination of external pumps and valves such as are usually present in such devices, by providing a self-contained hydraulic ram carriage.

Another feature of my invention is the provision of an auxiliary left-hand control which may be used when it is desired to free the right hand of the operator for some other purpose.

Still further advantages are inherent in my invention and how those as well as the objects hereinabove particularly mentioned are achieved will be best understood from the following detailed explanation of a presently preferred embodiment, for which purpose I shall refer to the accompanying drawings in which:

Fig. 1 is a front elevation;

Fig. 2 is an enlarged top plan view;

Fig. 3 is an enlarged fragmentary front elevation;

Fig. 4 is an enlarged fragmentary view taken on line 4—4 of Fig. 1;

Fig. 5 is an enlarged fragmentary section taken on line 5—5 of Fig. 3;

Fig. 6 is an enlarged cross section taken on line 6—6 of Fig. 3;

Fig. 7 is an enlarged cross section taken on line 7—7 of Fig. 3;

Fig. 8 is an enlarged fragmentary view taken on line 8—8 of Fig. 1;

Fig. 9 is a fragmentary vertical section taken on line 9—9 of Fig. 6; and

Fig. 10 is an enlarged fragmentary elevation of the lower end portion of a valve-operating shaft.

Referring now to the drawings, I show the supporting frame of my press as consisting of uprights 5 which may be anchored to the floor by angle iron brackets 6. The hydraulic ram carriage 7 is disposed between companion cross plates 8 secured to the frame by bolts 9 carrying spacer sleeves 9a. Horizontal plates 10, 11 are secured to the cross members 8 by bolts 12. The lower plate 11 has a medial opening 11a to pass the carriage, bearing surfaces being provided for the carriage by blocks 11b carried by plate 11.

20 A work-holding bed 15 is raised and lowered on the frame by means of cables 16 which are windable at one end about windlass 17, extending over sheaves 18 on the frame and connected at their other ends to the bed. The bed is retained at the desired working height by means of pins 20 extending into selected ones of the drilled holes in the frame uprights. Work W is shown supported on the bed by supporting blocks B.

25 The carriage 7 consists of a body 25 having vertical cylinder bores 26, 27 and a hydraulic fluid reservoir 28. A pumping piston 29 is reciprocally mounted in the cylinder 26 and is secured at its top end to a rack 30 by screw means 31.

30 A relatively large work piston 33 is reciprocally mounted in cylinder 27 and is stationarily secured at its top end to plate 10 by screw 33a, so that piston 33 remains stationary while the body 25 moves up and down through plate 11 relative to the piston. In the lower end of the body there is a horizontal bore 35 within which a valve housing 36 is secured by means of a snap ring 37. A vertical bore 38 is provided in the body and communicates at its top end with the reservoir.

35 A poppet valve 40 having stems 40a, 40b is normally held against its seat 41, provided at the inner end of a bore 42 in the valve housing, by spring 43. A transverse opening 44 through the housing communicates with an annular chamber 45, which chamber in turn communicates with cylinder 26 through passageway 47. There

40 is a counter bore 50 in the housing 36 within which a plug 51 is threadedly secured. The inner end of the plug has opening 53 providing a seat for a ball valve 55 controlling passage of

fluid between cylinder 26 and cylinder 27 and normally preventing escape of fluid from cylinder 27, there being a body passageway 21a providing communication between cylinder 27 and a transverse opening through plug 51 communicating with the hollow interior of the plug. A spring 56 normally urges valve 55 against its seat. Access to the valve housing is provided by a removable plate 58 carried by the body 25. Packing rings 59 are provided between the valve housing 36 and the body and packing rings 60 are also provided between the plug 51 and the valve housing. The bottom end of the body presents a nose or ram member 65.

A pair of spaced parallel posts 70 extend upwardly from plate 10 and a horizontal top plate 72 is supported atop the posts, the plate being secured in the position by bolts 74, 74a. Posts 70 are held in spaced relation by bolts 73 and spacers 73a. A shaft 75 is journaled for rotation in posts 70 and carries between the posts a pinion 76 whose teeth mesh with the teeth in the rack 30. Collars 77 are secured on the shaft 75 at the sides of the posts 70.

Shaft 75 is journaled adjacent its right end in a housing 80 secured to plate 72 by bolt 81, and a bevel gear 84 is secured on the right end of the shaft. The left end of the shaft 75 is journaled in another housing member 86 carried by top plate 72 and another bevel gear 85 is secured on the left end of the shaft.

A capstan 90 is operatively connected to shaft 75 by bevel gears 92, 93, shaft 94, clutch 95, shaft 94a and bevel gear 96, the latter meshing with gear 84, so that oscillation or rotation of the capstan moves the piston 29 by means of the pinion 76 and rack 30.

The clutch 95 consists of a collar 100 slidably but non-rotatably secured on shaft 94a, having an annular recess 101 and a toothed bottom end 102, and a collar 103 secured on the top end of shaft 94 and presenting a lateral clutch pin 104 engageable between teeth provided by the bottom end 102 of the collar 100. A bifurcated lever 106 is pivotally secured between its ends to a bracket 107 supported on the frame and has on its bifurcated outer end trunnions 108 projecting into the recess 101. A spring 106a connected to lever 106 and an arm on bracket 107 urges the clutch collar 100 downwardly into position engaging collar 103.

A foot pedal 110 is pivotally connected at one end to one of the frame uprights 5 and is operatively connected adjacent its free end to the lever 106 by rod 111 and link 112. The free end of lever 106 is normally urged upwardly by spring 115, but the pedal may be set in adjusted position by a stepped stop member 116 carried by the frame. A spring 116d urges pedal 110 towards the uprights to retain the pedal in engagement with the stop member.

Referring again to the hydraulic unit 7, within vertical bore 38 I rotatably dispose a shaft 120 whose upper end is secured in a collar 120a journaled in plate 10 and whose tubular intermediate portion 120c is rotatably disposed longitudinally in bore 38. A rod 120b of square cross section has its bottom end engaging in a squared socket in collar 120a. Secured in the lower end of the shaft portion 120a there is a round solid member 120d (Fig. 10) which has four longitudinal slots 120e to pass hydraulic fluid from the reservoir. On the bottom end of member 120d there is a reduced diameter portion 120f offset from the longitudinal axis and a cam 121 is ro-

tatably mounted on portion 120f. The projecting lower end of shaft portion 120f is journaled in a reduced portion of bore 38. When the shaft is rotated, cam 121 engages and pushes the stem 40a inwardly to first unseat poppet 40, and further rotative movement of the cam causes stem 40b to engage and unseat ball 55. The top end portion of rod 120b is of round cross section and is journaled to top plate 72.

Operation of the clutch 95 and the cam 121 is as follows: In the position in which the parts are illustrated in the various views of the drawings, the clutch is engaged and cam 121 is out of engagement with the valve stem 40a, so that the device is ready to commence operation of the plunger 29 to move the ram into contact with the work. After the pressing operation has been completed and it is desired to release the pressure from the cylinders, the foot pedal 110 is pressed downward and engaged below one of the stop shoulders 116a or 116b of stop member 116. This movement pulls rod 111 downwardly, fulcruming lever 106 about its pivotal connection to bracket 107 to lift the clutch collar 100 into disengaging position. That movement simultaneously swings post 136, which is carried by and projects upwardly from lever 106, to the left (Fig. 4), causing its carried cross pin 131 to engage and swing the triangular plate 132 about its pivotal connection 133 to the top plate 72. A link 134 is pivotally connected at 136 to a crank 137 secured to the rod 120b and thus such movement of the foot pedal causes rotation of the shaft 120 to move the cam into engagement with the valve stem 40a. A spring 138 is connected at one end to the crank 137 and at its other end to the top plate 72 so that it normally urges the crank into the position shown in Fig. 2, in which position the cam 121 is out of engagement with the valve stem 40a.

The hydraulic unit 7 is normally urged upwardly into the position of Fig. 3 by means of a pair of coil springs 140 connected at their top ends to the top plate 72 and connected at their bottom ends to the respective arms 142 carried by the body 25.

It will be observed that the work piston 33, being secured to plate 10, remains stationary while the body 25 of the hydraulic unit moves relative thereto. Thus, for the purpose of admitting hydraulic fluid into the cylinder 27 below the piston as the ram is initially moved relatively rapidly into contact with work in the manner to be hereinafter explained, I provide in the body a valve housing 150 secured in a corresponding bore in the body by means of a snap ring 151, and communicating with that bore I provide a passageway 152 which communicates with the reservoir 28. The valve housing 150 has a longitudinal bore closed at one end by a threaded plug 154 and has a transverse opening 155 communicating with cylinder 27. A poppet valve 158 is urged against its seat by coil spring 159 to normally close the reduced opening extending between passageway 152 and the interior of the valve housing. Thus as the body 25 initially moves downwardly relative to the piston 33, the vacuum created in the cylinder 27 unseats poppet 158 and draws fluid from the reservoir into cylinder 27. Within a bore in poppet 158 I provide a safety poppet valve 160 which seats against the periphery of the opening through a plug 161 threaded into poppet 158. A coil spring 162 urges poppet 160 into seated position.

To operate the ram, commencing with the
